METAL BURIAL CASKET

Frederick T. Paden, Collingswood, N. J.

Original application October 8, 1946, Serial No. 701,861. Divided and this application May 18, 1948, Serial No. 27,812

5 Claims. (Cl. 27—6)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

This application is a division of my application Serial No. 701,861 for Metal burial casket, filed October 8, 1946.

This invention relates to a metallic receptacle, and more particularly, to a metallic burial casket.

An object of this invention is to provide an improved metallic receptacle open at the top and provided with a lid and in which the receptacle and lid are provided with outwardly extending flanges forming a joint between said receptacle and lid, and in which reinforcing angle members are secured to the flanges wherein the vertical portion of one of the angle members overlaps the joint and the vertical portion of the other angle member provides a means for securing a molding to the upper portion of the receptacle.

Another object of this invention is to provide an improved metal burial casket in which the main body is of seamless sheet metal construction and flanged outwardly at the top, and in which the lid is also of seamless sheet metal construction and flanged outwardly at its perimeter to form a joint with the flange of the body, and in which a gasket is provided between the flanges, and securing means are provided passing through the flanges outwardly of the gasket so that the seal-tight character of the casket is preserved.

It is a still further object of this invention to provide an improved metallic burial casket of seamless sheet metal construction in which the bottom of the casket is convexed downwardly and is supported by a cradle, in which the upper portion of the body is flanged outwardly to receive a lid thereon with a gasket sealed therebetween, in which the lid is secured to the flange of the body and outwardly of the gasket seal, and the cradle is secured to the bottom of the casket body by means welded to the exterior of the casket body so that the casket is not pierced and the seal-tight character of the casket is preserved.

Other objects and advantages of the present invention will appear in the following detailed description and will be pointed out particularly in the appended claims, reference being had to the accompanying drawings forming part of this specification and in which:

Figure 1 is a front elevational view of the metallic receptacle of this invention;

Figure 2 is a plan view of the metallic receptacle

2

of this invention and with the lid and gasket cut away to show the main body flange;

Figure 3 is a transverse sectional view through the receptacle of this invention and showing a half portion of the receptacle;

Figure 4 is a transverse sectional view through the cradle structure of this invention and showing its manner of connection to the main receptacle body;

10 Figure 5 is a fragmentary sectional detail view showing the joint structure between the lid and the receptacle body;

Figure 6 is an enlarged fragmentary sectional view showing the means for securing the cradle structure to the receptacle body.

Referring to the drawings, the receptacle or casket of this invention is composed of a main body portion 1 of seamless sheet metal construction and which is preferably formed by deep

20 stamping of a unitary sheet. At the bottom of the main body portion 1 there is provided a supporting cradle denoted generally by reference numeral 2, also of stamped sheet metal construction. At the top of the main body portion 1 there

25 is provided a seamless sheet metal lid, denoted generally by reference numeral 3. The lid 3 is also preferably formed by stamping. As shown in Figure 1, the sides of the receptacle body 1 are provided with suitable hand rails 4 secured

30 in brackets 5 suitably secured to the exterior of the body 1. The design of the hand rail bracket structure and the general design of the casket shown in Figure 1 are covered in co-pending design applications, Serial Nos. D. 131,670, D. 131,

35 671, and D. 131,672, all filed July 18, 1946. Application Serial No. D. 131,670 is now Patent No. Des. 153,165 and application Serial No. D. 131,672 is now Patent No. Des. 151,166, both dated March

22, 1949, and application Serial No. D. 131,671 is abandoned. The upholstery 1' shown in Figure 2 is of conventional type and forms no part of the present invention.

As clearly shown in Figures 3 and 4, the cradle structure 2, formed of resilient sheet metal construction, is provided with a central upper portion 6 and side upper portions 7 for directly engaging the convex bottom 8 of the main body 1. When the cradle is in secured position as shown in Figure 3, the portions 6 and 7 have the same

50 convexity as the bottom 8 of the casket body so as to provide a substantial supporting surface. To enable the cradle 2 to be positioned on a flat horizontal surface, it is provided with intermediate lower portions 9 positioned between and below the portions 6 and 7 and lying in a substan-

55

cially horizontal plane. The outer ends of the cradle 2 are provided with moldings 10 formed by extending the sheet metal of cradle 2 downwardly and outwardly, and then upwardly and inwardly, as shown in Figures 3 and 4. Although the cradle 2 is illustrated as being formed of separate sections each of which may be easily stamped and which sections are connected together at the base of the molding 10, it is within the scope of this invention to form cradle 2 of a single sheet of metal. The molding 10 extends continuously around the cradle and if desired can be made of several lengthwise sections suitably joined together. The extreme ends of the cradle 2 are inturned under the body 1 as at 11, the portions 11 being adapted to closely engage the portions 12 of the body 1, which portions 12 are concaved downwardly and interconnect the walls 13 and the downwardly convex bottom 8 of the body 1. To secure the cradle 2 to the bottom of the casket body, there is provided a plurality of stud bolts 14 at spaced intervals around the bottom 8 and welded to the exterior of the bottom 8, as shown in detail in Figure 6. It is to be noted that the bolts 14 do not pierce the main body of the casket and thus the seal-tight character of the casket body is not destroyed by the securing means for the cradle 2. To complete the securing means, for each bolt 14, there is provided a threaded nut 15 which threads onto the bolt 14 passing through an opening 16 in the cradle 2 at portion 7 thereof. The securing means 14, 15 are provided at spaced intervals along the casket to provide for firm engagement between the cradle 2 and the bottom of the casket body.

In order to provide for a tight fit between the cradle and the casket body, the cradle 2 is formed with the portions 6, 7, and 11 thereof normally lying in a curvature of greater convexity than that of the bottom of the casket body so that when the portions 6 and 11 contact the bottom of the casket body, the portions 7 will lie in slightly spaced relationship from the bottom of the casket body as seen in Figure 4. Then when the nuts 15 are threaded tightly onto the bolts 14, the portions 7 of the cradle will be carried up tightly against the bottom of the casket, and due to the resilient structure of the sheet metal cradle 2, this will force portions 6 and 11 more tightly against the bottom of the casket body to form a wedge or press fit. This action is clearly illustrated in Figure 4 where the parts are shown in position immediately prior to tightening of the securing means 14, 15. In order to facilitate shipping the caskets or receptacles in a shipping case or crate, there are provided a number of studs 17 which are tapped to receive any suitable shipping bolt for tying the casket or receptacle down in the shipping case or crate.

The upper portions of the walls 13 of the main body 1 are bent outwardly to form an endless flange 18 around the opening to the body 1. The outer extremity of the flange 18 is down-turned at 19, as clearly shown in Figures 3 and 5. Also, the flange 18 is provided with an upwardly formed bead 20 for a purpose to be described hereinafter. In order to reinforce the flange 18, a reinforcing angle member or members 21 are provided all around the body 1, as shown in Figures 3 and 5. The angle members 21 having their horizontal portions 22 suitably secured as by welding or by mechanical means to the under surface of the flange 18. The down-turned portion 19 of the flange 18 is bent over the reinforcing angle members 21, as illustrated. The vertical portions 23

of the angle members 21 extend downwardly and are positioned outwardly of the horizontal portions 22 and are spaced from the walls 13 of the body portion 1, as shown in Figures 3 and 5. An upper molding 24 extends continuously around the upper portion of the casket body 1 and has its upper portion abutting down-turned portion 19 at 24' and overlapping and secured to the vertical portions 23 of the angle members 21 by means of suitable spaced screws 25 or by welding. The lower portion of the molding 24 is bent upwardly at 26 and is received by the retaining clips 27, suitably spaced and secured to the walls 13 of the body portion 1. In applying the molding 24, the portion 26 thereof is wedged under the retaining clips 27 and when the screws 25 are applied or moulding welded, the side edge 26 is held by the resiliency of the sheet metal material of which the molding 24 is constructed. If desired, the molding 24 can be made of either a single or several longitudinal sections suitably joined together to encircle the body 1.

The lid 3 has its perimeter flanged outwardly as at 28 for cooperation with the endless flange 18 to form a joint between the lid 3 and the main body portion 1. The flange 28 is provided with a downwardly formed bead 29 for a purpose to be described hereinafter and as clearly shown in Figures 3 and 5. Also, in order to reinforce the sheet metal flange 28 a reinforcing angle member or members 30 are provided with their horizontal portions 31 suitably secured, as by welding, or by mechanical means, to the top surface of the flange 28 and with their vertical portions 32 extending downwardly and outwardly of the angle member 21 and the molding 24, and in such manner as to overlap the joint between the flanges 18 and 28.

In order to provide a tight seal between the lid 3 and body portion 1, there is provided an endless gasket 33 which extends continuously around the casket opening to provide an air-tight construction when the lid is secured. The gasket 33 is preferably suitably secured as by an adhesive or other suitable means either to the lid 3 or the body portion 1, and is positioned to cooperate with the beads 20 and 29, as clearly illustrated in Figures 3 and 5. As seen in these figures, the beads 20 and 29 are positioned in offset overlapping relationship and are wedged against the gasket 33 to form in effect an S-joint to further provide an air-tight construction. Also, it is to be noted that the gasket 33 is enlarged inwardly so that it flares as illustrated to closely fit the inwardly diverging surfaces of the lid and the main body. This provides a wedge construction so that any attempted escape of air from the receptacle or casket will tend to wedge the gasket more tightly into contact with the surfaces of the lid and body and thus render the gasket still more air-tight.

In order to provide a securing means for holding the lid 3 down tightly against the gasket 33, a number of suitable bolts 37, as shown in Figure 3, are provided at spaced intervals around the periphery of the lid 3, the bolts passing through the flanges 18 and 28 and through the horizontal portions of the reinforcing angle members 21 and 30. The bolts 37 are preferably of the cam action type, which may be secured by turning the bolts 37 a quarter turn. Also, preferably the bolts 37 are provided with a spring means to raise the bolt to an upper position when released so that one can ascertain at a glance that the bolt is not in locking position. A number of these bolts are

available on the market and any one will serve the purpose of this invention. The bolts 37 are positioned outwardly of the gasket 36 so as not to affect the seal-tight character of the casket which is not pierced inwardly of the gasket 36. In final assembly the lower portions of the bolts 37 are concealed by the molding 24.

It is evident that applicant has provided a seamless receptacle or casket of sheet metal construction which has a deep stamped main body and a stamped lid, and in which suitable reinforcing angle members are provided at the joint between the body and the lid, and that the reinforcing angle members are utilized to cover the joint, and carry the upper molding of the casket body, and in such a manner that the securing means passing through the flanges has its lower end concealed by the upper molding. Also, it is to be noted that neither the lid nor the casket body is pierced at any point in a manner to destroy the air-tight character of the casket since the bolts 37 pierce the flanges outwardly of the gasket 36 and all elements fastened to the exterior of the casket body 1 are secured by fastening means which do not pierce the body 1; as for example, the retaining clips 27 and the stud bolts 14 are welded to exterior of the body 1 to preserve its seal-tight character. It is also to be noted that the cradle structure 2 provides a support for the casket so that it may be supported on a flat surface, and that the cradle structure specifically provides for a lower molding 10 in keeping with the upper molding 24, and which lower molding is provided with a finger space behind it so that it can also be used as a handhold. At the same time the finger space provides access to the fastening means 14, 15 so that the cradle 2 can be secured to the bottom of the casket body. It is apparent that applicant has provided a receptacle or casket construction which is air-tight, lightweight, and of durable construction. Also since the lid 3, the body 1, and cradle 2 are of stamped sheet metal construction, the casket parts may be readily stamped and quickly assembled on a mass production basis.

Though this invention is particularly applicable to metallic caskets, it is not limited thereto since the features of this invention are equally applicable to other metallic receptacles or receptacles made of other materials such as wood, plastics, etc., and the use of the term casket, as used in the specification and claims, should be read to cover other types of receptacles as well.

While the invention has been described in more or less detail, it is not to be limited thereby as changes may be made in the form, arrangement and construction of parts, and equivalents may be substituted without departing from the spirit and scope of the invention as claimed, the form hereinbefore described being merely a preferred embodiment thereof.

I claim:

1. A metallic receptacle comprising a main body portion of sheet metal construction and provided with upwardly extending side and end walls and a top opening, said side and end walls having their top portions bent outwardly to form a continuous horizontally extending flange of sheet metal around said opening, a sheet metal lid for said body portion, said lid having its perimeter formed into a continuous horizontally outwardly extending flange cooperating with said first-mentioned flange to form a joint, and reinforcing angle members having their horizontal portions secured to the respective flanges to strengthen same,

the vertical portion of the angle member secured to said first-mentioned flange being spaced outwardly from said respective walls, and the vertical portion of the angle member secured to said second-mentioned flange being positioned outwardly of the angle member secured to said first-mentioned flange and overlapping the joint between said body portion and said lid.

2. A metallic receptacle comprising a main body portion of sheet metal construction and provided with upwardly extending walls and a top opening, said walls having their top portions flared outwardly to form an endless horizontally extending flange around said opening, a sheet metal lid for said body portion, said lid having its perimeter formed into an endless horizontally extending flange cooperating with said first-mentioned flange to form a joint, an endless reinforcing angle member having its horizontal portion secured to said first-mentioned flange to strengthen same, the vertical portion of said angle member being spaced outwardly from said walls, and an endless sheet metal molding having one side connected to the vertical portion of said angle member and the other side connected to said walls.

3. A metal burial casket comprising a main body portion of sheet metal seamless construction and provided with upwardly extending walls and a top opening, said walls having their top portions flared outwardly to form an endless horizontally extending flange around said opening, a seamless sheet metal lid for said body portion, said lid having its perimeter formed into an endless horizontally extending flange cooperating with said first-mentioned flange to form a joint, reinforcing angle members having their horizontal portions secured respectively to said flanges to strengthen same, means passing through said flanges and the horizontal portions of said angle members for securing said lid to said body portion, and an endless gasket between said flanges and positioned inwardly of said securing means, said flanges being formed with overlapping beads, respectively, to engage said gasket when said lid is in closed position on said body portion.

4. A metal burial casket comprising a main body portion of sheet metal construction and provided with upwardly extending walls and a top opening, said walls having their top portions flared outwardly to form an endless horizontally extending flange around said opening, a sheet metal lid for said body portion, said lid having its perimeter formed into an endless horizontally extending flange cooperating with said first-mentioned flange to form a joint, reinforcing angle members having their horizontal portions secured respectively to said flanges to strengthen same, the vertical portion of the angle member secured to said first-mentioned flange being spaced outwardly from said respective walls, and the vertical portion of the angle member secured to said second-mentioned flange being positioned outwardly of the angle member secured to said first-mentioned flange and overlapping said joint.

5. A metal burial casket comprising a main body portion of sheet metal construction and provided with upwardly extending walls and a top opening, said walls having their top portions flared outwardly to form an endless horizontally extending flange around said opening, a sheet metal lid for said body portion, said lid having its perimeter formed into an endless horizontally extending flange cooperating with said first-mentioned flange to form a joint, reinforcing angle

members having their horizontal portions secured respectively to said flanges to strengthen same, the vertical portion of the angle member secured to said first-mentioned flange being spaced outwardly from said respective walls, and the vertical portion of the angle member secured to said second-mentioned flange being positioned outwardly of the angle member secured to said first-mentioned flange and overlapping said joint, an endless sheet metal molding having one side connected to the vertical portion of the angle member secured to said first-mentioned flange and the other side connected to said walls, and securing means passing through said flanges and the horizontal portions of said angle members and

having their lower ends concealed by said endless molding.
